UNITED STATES PATENT OFFICE

HOWARD W. GILBERT, OF NAZARETH, PENNSYLVANIA

AUTOMATIC WINDOW LATCH

Application filed January 4, 1930. Serial No. 418,590.

This invention relates to improvements in latching devices and is designed particularly for use as a window sash latch.

The primary object of the present invention is to provide a latch which may be readily actuated for disconnecting one sash from another by the application of a pull to a cord which forms a part of the device and which is designed to suspend from the upper bar of the bottom sash of the window.

Another object of the invention is to provide a latch which may be directly controlled by the engagement of a finger under a movable element thereof or may be controlled from a distance through the medium of a pull cord as for example where the latch is used on very large windows where the division between the sashes would be located at a point beyond the reach of the average person.

A still further object of the invention is to provide a window latch of simple design, easy to manipulate, of strong and durable construction and of a character which will permit of its being economically produced.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:—

Figure 1 is a view in front elevation of a window equipped with the device embodying the present invention.

Figure 2 is a vertical sectional view through the contacting portions of the window sash and the latch device.

Figure 3 is a sectional view similar to Figure 2 showing the lower sash raised to bring the latch adjacent a mullion of the upper sash.

Figure 4 is a top plan view of the latch minus the keeper.

Figure 5 is a top plan view of the keeper.

Figure 6 is a rear view of the latch.

Figure 7 is a sectional view taken on the line 7—7 of Figure 3.

Figure 8 is a plan view of the bolt per se.

Figure 9 is a front elevation of a mullion guard.

Referring more particularly to the drawings wherein like numerals of reference indicate corresponding parts throughout the several views, the numerals 1 and 2 indicate respectively the upper and lower sash of a window frame, the meeting bars therebetween being indicated by the numerals 3 and 4, the bar 4 of course, as will be readily seen, constituting the top of the lower sash 2.

The latch embodying the present invention comprises an elongated housing 5 mounted upon a base 6 which, as shown, is secured to the top bar 4 of the lower sash so that one end of the casing or housing 5 is in a plane flush with the inner face of the bar 4.

The housing 5 is open at the end which is flush with the inner side of the bar 4 and intermediate its ends a depending wall 7 is formed which terminates at a point above the base 6 thus providing a passage 8 therebeneath which opens from the rear end of the housing into the chamber 9 in which the latch bolt about to be described reciprocates.

The latch bolt which works in the chamber 9 is indicated generally by the numeral 10, this member being hollow as shown and having the forward end face undercut as indicated at 11 while at the rear end extends therefrom the flat tongue 12 which projects through the passage 8 under the wall 7 into the rear of the housing, this tongue being provided with a longitudinally extending slot 13 and at its rear end with an eye 14 for the connection therewith of one end of a pull cord 15.

As shown the top of the housing 5 is cut away at the rear or back end thereof leaving only the spaced side wall portions 16. Pivotally mounted upon a pin 17 extending transversely of the upper part of the wall portions 16 is an oscillatable latch actuator 18 which is roughly in the form of an inward U, the pivot pin 17 extending through the

yoke portion 19 which connects the sides 20 and 21. The side 21 of the latch actuator 18 as shown normally bears against the rear face of the wall 7 and extends into the slot 13 5 in the rearwardly extending tongue of the latch bolt. The free end of the portion 20 of the latch actuator is transversely recessed as indicated at 22 and has pivotally mounted in this recess a roller 23 over which the pull 10 cord 15 passes.

Associated with the inner end of the casing 5 is a keeper 24 which, as shown, is secured to the bottom bar 3 of the adjacent or upper sash 1 so that the latch bolt 10 may project 15 thereinto when both sashes are in closed position.

In actuating the present latch bolt for the release of the sash, if the central portion of the window is low enough for a person to 20 conveniently reach the actuator 18, the outer arm 20 of this actuator may be raised or swung outwardly on the pivot 17 so that the inner arm 21 will oscillate and draw the latch bolt 10 back to disengage it from the 25 keeper 24. When the latch is thus drawn back a control spring 25 which is housed therein and bears at its forward end against the forward wall of the latch and at its rearward end against the inner face of the wall 30 7, will be compressed so that it will act to immediately project the latch outwardly again as soon as the actuator 18 is released. After retracting the latch bolt 10 and lifting the sash so that the bolt will be free from 35 engagement with the keeper 24 the sash may be freely raised.

In order that the bolt 10 may pass the transverse mullions of the sash where the 40 latch is used in connection with sash having a number of lights therein, I provide a guide element 26 in the form of a metal strip having a straight portion 27 which is secured to the face of the mullion and a curved portion 28 which extends downwardly and inwardly 45 therebeneath so that as will be seen, when the sash is moved upwardly, the point of the bolt will ride onto the curved portion of the guide strip and will be forced back into the housing 5 so that it may pass the mullion without damage thereto.

Where the latch is used for securing the sash of windows of such a size that the central part thereof cannot be conveniently reached, the bolt 10 may be retracted by pulling 55 upon the cord 15, the outer arm 20 of the actuator 18 here acting as a support and guide for the cord.

From the foregoing description it will be 60 readily seen that except for the actual releasing of the bolt 10 from its keeper, the operation of the present latch device is entirely automatic as the bolt is properly retracted during the raising of the sash to permit it to pass the mullions and this retraction is also carried out in the lowering 65

of the sash, the bolt automatically engaging in its keeper when the sash has been lowered to the completely closed position.

Having thus described my invention, what I claim is:—

1. In combination, a window latch having a reciprocable bolt and adapted to be mounted upon the top bar of a lower window sash, and a bolt guide and shifting element adapted to be mounted upon a mullion of an adjacent sash to shift said bolt when the first mentioned sash is lifted to permit the bolt to pass the mullion. 70

2. In combination, a window latch having a reciprocable bolt and adapted to be mounted upon the top bar of a lower window sash, and a bolt guide and shifting element adapted to be mounted upon a mullion of an adjacent sash to shift said bolt when the first mentioned sash is lifted to permit the bolt to pass the mullion, said bolt guiding and shifting element comprising a guide plate having a straight portion adapted to be secured to the mullion and a curved portion extending inwardly beneath the mullion. 80

3. A latch of the character described, comprising an elongated bolt casing having each end open, said casing at one end having a portion of the top thereof cut away, a wall depending from the edge of the casing top adjacent the cut away portion and partially closing the casing, a bolt slidably positioned in the casing and movable for projection from the end remote from the partition, a tongue extending rearwardly from the bolt beneath said partition and having a longitudinal slot therein, said bolt having the rear thereof open, a spring member having one end extended into the open rear end of the bolt and having its other end bearing against said partition, an actuator for the bolt comprising a substantially U-shaped member arranged in inverted position in the cut away rear portion of the casing and having the free end of one side extended downwardly into the slot of said tongue, said side of the actuator normally abutting said partition, a pivot pin connecting the actuator with the side walls of the casing, a pulley member carried by said actuator at the free end of the other side thereof, and a pull cord extending across said pulley and having one end connected with said tongue. 90

In testimony whereof I hereunto affix my signature.

HOWARD W. GILBERT.
